INVENTOR.

Charles F. Winder,
BY Blakeslee & Brown,
ATTORNEYS.

UNITED STATES PATENT OFFICE.

CHARLES F. WINDER, OF HOLLYWOOD, CALIFORNIA, ASSIGNOR TO THE SYMPHONAER CO., A CORPORATION OF DELAWARE.

ORGAN.

Application filed November 30, 1925. Serial No. 72,213.

This invention relates to organs, and particularly to means for controlling the expression or swell of an organ. At the present time the expression of an organ is 5 cured by what are known as Venetian shutters which are opened either separately or collectively. These Venetian shutters, however, by opening at an angle throw the tone to one side of an auditorium rather than directly into the auditorium.

My invention has for an object the provision of expression control means which throws the tone from the organ chamber directly in front. One bad feature of present 15 shutters as now used in organs is due to what may be termed distortion or out-of-tune of the various organ pipes, due to the fact that there is always a difference in temperature between the auditorium into which the music 20 is projected and the organ chamber, with the consequence that when the expression shutters are opened cooler air from the auditorium enters into the organ chamber and throws portions of the organ pipes out of 25 tune. This is particularly true where certain of the organ pipes are not susceptible to immediate change of temperature.

A further object of my invention is the provision of swell or expression control means which allows for equal temperature 30 between the auditorium and the organ chamber, and yet at the same time fully controls the swell crescendo effect.

Another object is the provision of a swell 35 or expression control means which is simple of construction, positive and rapid in action and which is generally superior.

With the above and other objects in view, the invention consists in the novel and useful provision, formation, construction, association and relative arrangement of parts, members and features, all as shown in certain 40 embodiments in the accompanying drawings, described generally and more particularly 45 pointed out in the claims.

In the drawings:

Figure 1 is a rear elevation of the front of an organ chamber incorporating the invention;

50 Figure 2 is a fragmentary cross sectional view of a portion of the invention, taken on the line 2-2 of Figure 1;

Figure 3 is a fragmentary elevation of one of the expression shutters used in practicing the invention;

Figure 4 is a vertical sectional view of one of the expression shutters;

Figure 5 is a transverse sectional view of three of the expression shutters taken on the line 5-5 of Fig. 3;

Figure 6 is a plan view of the expression shutters and control means therefor;

Figure 7 is a vertical sectional view of a certain type of motor which may be used for operating the expression shutters;

Figure 8 is a cross sectional view of the shutter drum and showing one of the shutters associated therewith;

Figure 9 is a fragmentary elevation of the shutters and drum; and,

Figure 10 is a plan view of a series of such shutters and operating means therefor; Figures 8, 9 and 10 being modifications of the shutter control mechanism.

Corresponding parts in all the figures are 75 designated by the same reference characters.

Referring with particularity to the drawings, the improved expression control means is designated as an entirety in one embodiment by A, of which a designates the shutters and b means for controlling movement of the shutters a. The shutters control the expression or swell effect of an organ, and to this end c represents an organ chamber having top and bottom walls 1 and 2 respectively, as well as side walls 3 and a front wall 4 joined with the top, bottom and side walls. The front wall is provided with a substantially circular opening 5, and the shutters a are adapted when in one position to completely be received within and enclose the said opening 5. The organ pipes are likewise within the organ chamber. As each shutter a is identical one of such shutters will be described, the same reference characters 95 applying to the others.

Referring to Figure 4, the shutter 2 is made in three parts, as indicated at 6, 7 and 8, with each part thereof spaced apart to provide two chambers 9 and 10. The wall 100 members of the shutter are carried by a base member 11 which is shouldered at 12 and 13 to hold and secure the walls 6 and 8 respectively, and which base member is likewise slotted or grooved at 14 to receive 105 the wall 7. The opposite end of such wall is carried by a top member 15 which is formed the same as the bottom member 11 and as a result the same reference characters 110 will apply. The top surface of the member

15 is curved as shown at 16 to correspond with the curvature of the opening 5, and such top member has projecting therefrom intermediate its length and width a pivot pin 17 which is received in a socket or opening 18 in the frame-work 19 surrounding the opening 5 of the front wall 4 of the organ chamber. The member 11 is provided likewise with a pivot pin 20 intermediate 10 its length and width. A drum 21 has its peripheral member 22 provided with a series of spaced transverse bores 23 within which is received the pin or pins 20. The shutter control means *b* includes in one embodiment 15 of the invention a bevel gear 24 keyed to or otherwise secured to the pin 20. Received within the drum and adapted to mesh with the teeth of the gear 24 or series of such gears, is a gear 25 which is keyed or 20 otherwise secured to a shaft 26, the shaft having a bearing in the front wall 27 of the drum as shown at 28, and with the opposite end portion of said shaft secured to a crank arm 29. If we assume a plurality of the 25 shutters *a* all pivotally mounted to the drum 27 with the said shutters and drum received in the opening 5, we may support the said shutters and shutter-operating mechanism in the position aforesaid, by a suitable standard *d* comprising in the present instance two uprights 30 and 31 which are braced by means 32 and 33 with a bearing piece 34 between such uprights. A sleeve 35 is carried on the shaft 26 and received within an 30 opening of the cross-piece 36. Endwise movement of this sleeve relative to the cross-piece is prevented by a collar 37 adapted to be locked to the sleeve, all as shown in Fig. 2. The arm 29 in turn may be connected to 35 a link or arm 38 for controlling rotation or movement of the arm 29. As each shutter is pivoted both at top and bottom, movement of the arm 29 will produce rotary movement of the gear 25 and in turn move the individual shutters *a* about their pivot axes. As I have pointed out, an auditorium is always 40 of a different temperature from the temperature in the organ chamber, with the result that when the expression shutters are open 45 the cooler air from the auditorium will enter into the organ chamber and those pipes in the organ chamber not susceptible to immediate change of temperature, will be out of tune. To overcome this I have perforated 50 the different walls, 6, 7 and 8 of each shutter, as shown in Figure 4, and the said perforations in each wall are in staggered relation to the next adjacent wall, with the result that sound from within the organ chamber 55 is not permitted to escape with any volume past the shutters when the shutters are all closed. This arrangement of the shutters permits the cooler air of the auditorium to enter through the said perforations in 60 the shutter walls, into the organ chamber 65

and maintain an equal temperature or approximately equal temperature between said auditorium and said organ chamber.

In Figure 5 I have illustrated a method of cutting the sides of the walls of the different shutters whereby they may readily swing apart to open or close the shutters, and at the same time permit little or no sound to escape between adjacent wall sides. This is accomplished by slanting the edge of 70 the wall 6 at one end thereof, as shown at 40. The intermediate wall is straight-sided while the wall 8 has one side or edge thereof slanted as shown at 41. By slanting I mean that the edge or edges are at an angle other 75 than right angles to the sides of the wall or walls. The general appearance in top plan, as Figure 5 shows, is a conventional letter **S** between the various edges. This method of forming the walls acts, as has been stated, as 80 a sound trap.

In Figure 6 I have shown a series of shutters mounted upon the drum *b*, and the arm or link 38 is directly connected to one of a series of pneumatic motors *m*. These motors take the form shown in Figure 7 in which each motor is provided with a disc 50 and with a flexible portion or a bellows 51 inter-connecting two of such discs. The discs are provided with ports 52 which open 85 outwardly of the disc and likewise inwardly of the bellows, and a tube or tubes 53 associated with the discs and the port or ports permit air to be forced between the discs to expand the bellows and thereby move the 90 discs relatively or to allow air to be exhausted from the bellows which will permit the bellows to collapse, this collapse being aided by a spring or the like associated with the link or arm 38. The link or arm has 95 a pivot bearing at 54 and with a second portion of said link or arm passed through a guide 55. The disc of the first motor *m* would be connected to the arm or link and the last motor would have its disc associated 100 with an abutment. When the link or arm moves outwardly the gear 25 will rotate the pinion gears 24 to move the shutters, as 105 shown in Figure 6.

A modified form of the shutter device is 110 shown in Figures 8, 9 and 10, and does not differ essentially from the device just described, the shutters being the same, and the main difference being that the pivot pins 20 for each shutter are not provided with gears 115 24. In the present form of the invention which I designate as an entirety by *B* each shutter *a* at the base thereof, is provided with an arm portion 60, and links 61 pivotally interconnect such arm portions. One 120 of such arm portions 62 is enlarged and has direct connection with the link 38. The principle of operation is the same as for the form *B* for when the link 38 is moved to move the arm shown at 62 the links 61 move 125

the arms 60 to open or close the shutters.

The advantage of shutter arrangement as disclosed by this invention will be apparent to musicians, in that the tone is permitted to escape from the organ chamber directly into the auditorium. The ordinary form of shutter as now used throws the tone to one side of the auditorium. The general effect of the arrangement of the walls of each independent shutter is, when the shutters are closed, that of two open rooms between the organ chamber and the auditorium. This gives a crescendo effect not possible with any other kind of shutter. Of course other means may be resorted to to equalize the temperature between the organ room and the auditorium, but the method herein shown is simple and very effective. A flue can be arranged in the organ chamber to draw in the air if desired.

It is obvious that various changes and modifications may be made in practicing the invention, in departure from the particular showing of the drawings, without departing from the true spirit of the invention.

Having thus disclosed my invention, I claim and desire to secure by Letters Patent:

1. Improvements of the character disclosed, comprising an organ chamber having an opening through which sound is adapted to be emitted from the organ chamber, and shutter mechanism confined in said opening, said opening being substantially circular; said shutter mechanism including a plurality of shutters arranged in circular formation; said shutters being formed to permit temperature equalization between the interior of the organ chamber and the exterior thereof.

2. Improvements in organs, including means for controlling the crescendo effect thereof, comprising a shutter provided with two spaced wall members.

3. Improvements in organs, including means for controlling the crescendo effect thereof, comprising a shutter provided with two spaced wall members, and means for moving the said shutter.

4. Improvements in organs having an organ chamber, and means for controlling the crescendo effect between said organ chamber and an auditorium, said means comprising a shutter between said organ chamber and auditorium, said shutter being provided with two spaced wall members and mechanism for moving said shutter.

5. Improvements in organs having an organ chamber, a chamber exterior the organ chamber within which music is to be projected from the organ chamber, and means

between the organ chamber and the second named chamber for controlling the crescendo effect from the organ chamber, said means comprising a shutter formed with a plurality of spaced wall portions, said walls of the shutters being provided with perforations whereby there may be an equalization of temperature between the organ chamber and the chamber exterior thereof.

6. Improvements in organs having an organ chamber, a chamber exterior the organ chamber within which music is to be projected from the organ chamber, and means between the organ chamber and the second named chamber for controlling the crescendo effect from the organ chamber, said means comprising a shutter formed with a plurality of spaced wall portions, said walls of the shutters being provided with perforations whereby there may be an equalization of temperature between the organ chamber and the chamber exterior thereof; said shutters being arranged in circular formation when closed, and mechanism for moving the said shutters to open and close the same.

7. Improvements in organs having an organ chamber, a chamber exterior the organ chamber within which music is to be projected from the organ chamber, and means between the organ chamber and the second named chamber for controlling the crescendo effect from the organ chamber, said means comprising a shutter formed with a plurality of spaced wall portions, said walls of the shutters being provided with perforations whereby there may be an equalization of temperature between the organ chamber and the chamber exterior thereof; said shutters being arranged in circular formation when closed, and mechanism for moving the said shutters to open and close the same; said mechanism including a motor, and mechanism inter-connecting the motor with the shutters whereby upon movement of the motor the shutters are simultaneously moved.

8. Improvements in shutters for organs, comprising a drum, a plurality of shutters rotatably mounted upon said drum, said shutters when revolved in one direction co-operating to form a wall.

9. In organ devices as disclosed, a shutter provided with two spaced walls.

10. In organ devices as disclosed, a shutter provided with two spaced walls, said walls having perforations therein, the perforations in one wall being in staggered relation relative to the perforations in the other wall.

In testimony whereof, I have signed my name to this specification.

CHARLES F. WINDER.
